UNITED STATES PATENT OFFICE.

KARL SCHMIDT, OF BERLIN-SUDENDE, GERMANY, ASSIGNOR TO C. LORENZ AKTIEN-
GESELLSCHAFT, OF BERLIN-TEMPELHOF, GERMANY.

MEANS FOR FREQUENCY MULTIPLICATION.

Application filed March 9, 1925, Serial No. 14,259, and in Germany February 15, 1924.

My invention relates to an improved method of and means for the multiplication of frequencies occurring in alternating electrical phenomena, and is especially applicable in connection with radio transmission.

As is well known it has become possible in high frequency working to obtain in the simplest manner high multiplication of the initial frequency by means of iron-cored transformers magnetized by an alternating current. Wave lengths of 600 m. have been obtained with an initial wave length of 42 km. according to the initial number of periods. For these long wave lengths the high frequency alternator is, on account of the constancy and the stability of the oscillations produced by it since a long time superior to vacuum tubes, as a generator for space telegraphy. In the case, however, of high multiplications such as mentioned in the example—70 times the original frequency—very high iron losses take place in the transformer itself which considerably reduce the efficiency of the installation, so that the valve transmitter having a better efficiency than a high frequency alternator is still superior, in the case of shorter waves, to high frequency alternators. The reason for it is that the low initial frequency requires a relatively large transformer in order to give corresponding production in the case of small wave lengths. It follows therefrom that the transformer, owing to the high self induction in the case of small wave lengths or to the high secondary frequency, is raised to a very high tension which leads to difficulties in the insulation of the transformer. My invention, on the one hand, materially improves the efficiency of the frequency multiplication, more particularly in the case of high multiplication, and on the other hand avoids high tension in the primary transformer and permits the obtaining of an increase of frequency with good efficiency up to 250 m. waves with the initial wave of 42 km.

According to my invention the multiplication is carried out in two steps by means of two transformers, in such a manner that only a slight multiplication is effected in the second step. If for instance the frequency has to be multiplied 85 times, in the first stage the 17-fold and in the second stage, the 5-fold frequency can be produced. Although the fundamental frequency of the alternator,

the proportions of the transformers and the kind of iron used in them have a great influence to the working of frequency changers I have found that, with the iron obtained in the trade for use in high frequency transformers frequencies may be changed to a 13-fold up to a 17-fold with an eminently good efficiency. Consequently the multiplication is carried in the primary transformer only to nearly the 13-fold frequency, and a further multiplication corresponding to the desired wave length is carried out in the second transformer.

On the other hand, practical experiments have shown that when using frequency transformers magnetized by an alternating current, the number of higher harmonics increases with the magnitude of the multiplication. Sometimes these higher harmonics are developed with so great an amplitude that the well known means for suppressing them by loose coupling the aerial circuit is not sufficient. Better well known means for suppressing higher harmonics is the use of an intermediate circuit. Such an intermediate circuit has, however, a still more unfavorable effect on the efficiency of the whole installation than loose coupling of the aerial circuit. Its manipulation is complicated, as the intermediate circuit has to be adjusted afresh for each wave, and tuned again.

In employing my invention an intermediate circuit may be dispensed with the method being based on the fact that in the case of small multiplications as in the second step according to my invention, as already stated, no higher harmonics worth mentioning are produced. Thus when the 5-fold frequency is produced, practically no higher harmonics will appear. If the frequency were straight-away multiplied eighty-five times by means of one transformer, so many higher harmonics would be produced that they could be eliminated to a certain extent only by means of an intermediate circuit.

The two accompanying drawings are diagrams of connections showing by way of examples two forms embodied in my invention:

Fig. 1 showing the connections of two circuits coupled by a self induction without an iron core,

Fig. 2 showing connections for producing oscillations free from higher harmonics.

According to both figures G is the high

frequency generator which is coupled to the self induction L of the fundamental (natural) frequency circuit. This self induction L is connected in series with the condenser C and with the iron-cored frequency transformer T_1 . This circuit is tuned in a well known manner to resonate with the generator frequency and according to my system of frequency multiplication this resonance is adjusted to a critical value to be denoted as critical resonance condition by giving the inductance L a relatively large value. The iron core of the frequency transformer T_1 is dimensioned to be saturated by a fractional part only of the peak value of the current. The self-induction of the circuit (coil L) is given such a value with respect to the capacity C , that by virtue of the saturation of the core and the corresponding alteration of its magnetic permeability the tuning of the circuit $L C T_1$ is periodically changed from a condition of resonance (critical resonance) to a condition of non-resonance. The magnetic flux of the core changes suddenly each half-cycle from its positive to its negative saturation value. Short tension peaks periodically follow each other at regular intervals which produce by shock excitation damped wave trains of the natural frequency of the secondary circuit (e. g. 13-fold the fundamental frequency). By virtue of the regularly occurring impulses quickly following each other a practically undamped wave is produced.

To the self induction L , is coupled the transformer T_2 ; this coupling could be effected directly or, which is preferable, with the interposition of a condenser C_2 . The oscillation circuit L_1, C_2, T_2 is then tuned to the same multiplied frequency as in the case of the circuit C_1, T_1, L_1 , namely in such a manner that the critical point of resonance condition is obtained also in this circuit. Parallel to the winding of the transformer T_2 , is connected another oscillating circuit with the self induction L_2 and capacity C_3 , which is then tuned to the desired wave.

According to another mode of connection represented by Fig. 2, the primary circuit of the second frequency transformer is directly

included into the secondary circuit of the first transformer. The reference numbers in Fig. 2 are the same as in Fig. 1, the difference only existing in that the secondary (output) circuit T_1, C_1, T_2, L , of the frequency transformer T_1 , forms at the same time the primary (input) circuit of the second frequency transformer T_2 including the second transformer L_2 . An antenna A is coupled with the secondary circuit of the second transformer L_2 as shown.

The coupling of the frequency multiplying circuit may be made by a capacity also instead of an inductance L as represented by the diagram of Fig. 1.

While I have described my invention in certain preferred embodiments I desire that it be understood that modifications may be made and that no limitations are intended other than may be imposed by the scope of the appended claims.

What I claim is:

1. In a high frequency multiplication system of the character described for changing a fundamental frequency into a higher frequency comprising in combination an iron cored frequency multiplication transformer having its input circuit fed by current of said fundamental frequency, a second frequency multiplication transformer connected in cascade with said first frequency transformer and having a multiplication ratio relatively small with respect to that of the first frequency transformer.

2. In a high frequency multiplication system of the character described for changing a fundamental frequency into another higher frequency comprising in combination an iron-cored frequency transformer having its input circuit fed by said fundamental frequency, a second frequency transformer having a multiplication ratio relatively small with respect to that of the first frequency transformer and means for coupling the output circuit of the first transformer with said input circuit of said second transformer.

In testimony whereof I have affixed my signature.

KARL SCHMIDT.
